COMBINED CEMENTED AND TURNED SHOE
AND METHOD OF MAKING SAME

William Shimkowitz, Brooklyn, N. Y.

Application March 13, 1931. Serial No. 522,305

6 Claims. (Cl. 12—142)

My present invention relates generally to footwear, and has particular reference to turned shoes, and, coordinate, to an improved and novel method of constructing such shoes.

5 It is a general object of my invention to provide a shoe of improved characteristics, especially with respect to the outward appearance thereof and the manner in which the several parts are associated. More particularly, it is an 10 object of my invention to provide a shoe construction, and a method of producing the same, whereby all the advantageous characteristics of turned shoes are obtained, while many of the disadvantages thereof are obviated.

15 The better class and relatively expensive shoes are customarily of the turned variety, having a high-class and stylish outward appearance and embodying careful and staunch workmanship. On the other hand, the procedural steps involved 20 require highly skilled labor and are relatively expensive. Also, although the contour of the shoe at the forward portion thereof is usually of enhanced character, difficulties are sometimes encountered in obtaining the requisite smooth 25 contour at the shank portion of the shoe.

In a shoe construction where the sole is cemented into position, the extreme simplicity of the procedure and of the finished shoe results in minimum expense, but the completed article is 30 not as high-class or as stylish as the turned variety. On the other hand, a better fit and contour at the shank can usually be attained by the cementing procedure.

35 My present invention aims to combine the advantageous features of both of these well known processes, and has for its object the provision of a shoe which is in part a turned shoe and in part a cemented shoe. My invention relates also to a method of carrying out this general objective.

40 It is a feature of my invention, for example, to construct the forward portion of the shoe in much the same manner as turned shoes are made, and to construct the shank and rear portions of the shoe in a manner similar to that heretofore 45 carried out in connection with cementing procedures.

A further feature of my invention lies in arranging an insole member in association with an outer sole and an upper in such a manner that 50 the finished shoe is of a highly efficient and rugged, yet attractive and stylish, character.

A still further object of my invention lies in the provision of a novel type of sole member or element which finds particular applicability in 55 the carrying out of the present invention.

I achieve the foregoing objects and advantages, and such other objects and advantages as may hereinafter appear or be pointed out, in the manner illustratively exemplified in the accompanying drawings, wherein—

60 Figure 1 is a plan view of a sole member constructed in accordance with my present invention;

Figure 2 is a fragmentary cross-section taken substantially along the line 2—2 of Figure 1;

Figure 3 is a fragmentary cross-section taken substantially along the line 3—3 of Figure 1;

Figure 4 is a view similar to Figure 1, showing the sole member in position upon a last with an upper associated therewith in accordance with the present invention;

Figure 5 is a perspective view of an assembly upon a last, showing a further stage of the procedure;

Figure 6 is a perspective view of a completed 65 shoe of the present character;

Figure 7 is a perspective view of a sole member of slightly modified construction;

Figure 8 is a perspective view of a shoe embodying the sole member of Figure 7 and partially completed;

Figure 9 is a view similar to Figure 8, showing the shoe in completed condition;

Figure 10 is a perspective view from underneath, showing a shank stiffener insole member 85 of the character which may be employed; and

Figure 11 is a view similar to Figure 10, showing a modification.

The sole member 15 of Figure 1 may be of any suitable material, and is usually of a strip of leather of substantially uniform thickness, except that the shank and rear portions of the present sole member are marginally beveled while the forward portion is marginally shouldered. In Figure 1, the forward portion of the member is shown at the right, and it is noted that the periphery is reduced at the midportion to form what will ultimately be the shank portion of the shoe.

100 The forward portion is provided with a margin of reduced thickness, thereby defining a shoulder 16 disposed outwardly and lying adjacent to and slightly behind the peripheral edge of the member 15. This shoulder terminates at the points designated by the reference numerals 17 and 18, which is practically at the shank portion; and rearwardly of the points 17 and 18 the marginal edge of the member 15 is tapered or beveled, as at 19, the shoulder 16 merging with this tapered edge or margin.

110

Behind the shoulder 16 and paralleling the latter is a cut or channel 20 which extends obliquely downwardly toward the edge of the sole member 15 but does not extend entirely through 5 the sole member, as shown most clearly in Figure 2. This channel similarly terminates at the shank portion of the sole, and the shank and rear portions of the sole are therefore unshouldered and unchanneled.

10 In constructing a shoe of the present character, the lower edge of the forward portion of an upper is stitched to the forward marginally shouldered and channeled portion of the sole member 15 in such a manner that the assembly may thereafter 15 be turned to conceal the stitches. This may be accomplished in the manner illustrated most clearly in Figure 4. The forward portion of the sole member 15, viz., that portion which lies approximately to the right of the line 21 of Figure 20 1, is first moistened in order to make it more pliable. The member 15 is then tacked onto the upper face of a last, as, for example, by means of the tacks 22 of Figure 4. An upper 23 is then drawn over the last and the edge of the forward portion thereof is stitched, as at 24, to the shoulder 16, the stitches extending through this shoulder and into the channel 20. The upper usually 25 consists of a number of plies, including a lining, a box toe member, and the like; but for the purpose of describing the present invention, the reference numeral 23 has been applied to the upper as a unit.

In stitching the forward portion of the upper, as at 24, to the shoulder 16, the upper is arranged with its wrong side out, so that after the 30 rough edges are trimmed off, the assembly may be removed from the last and turned inside out, thereby concealing the stitches 24 and exposing not only the right side of the upper but also 35 concealing the shoulder 16 and leaving nothing but the reduced peripheral edge of the forward portion of the sole member 15 visible.

Prior to applying the stitches 24 the edge of the upper 23 may, if desired, be tacked into temporary position upon the last, as will be readily understood by those skilled in the art.

After the assembly has been removed from the last and turned, in the manner hereinbefore referred to, the assembly is placed upon the last 25 50 of Figure 5, to the under-surface of which an insole member 26 has been temporarily secured, as by tacks or the like.

Also, prior to the application of the assembly to the last 25, it is preferable to apply the desired counter to the rear portion of the upper.

Cement or similar adhesive is then applied to the marginal portion of the insole member 26 and the free, and as yet unattached, edge of the upper is drawn over the last and temporarily 55 held in firm engagement with the adhesively coated margin of the member 26 by means of tacks 27 or the like. This procedure permits the upper to be fitted snugly and efficiently to the contour of the last 25 so that when the shoe is ultimately completed the shank and rear portions thereof will have a smooth and highly attractive configuration and appearance.

After the adhesive bond between the member 26 and the upper 23 has reached a point where the tacks 27 are no longer necessary, the latter are removed, although it will be understood that certain of the tacks, especially the tacks 28 associated with the heel portion, may remain in permanent association with the finished construction, this being accomplished by inserting a

metal plate upon the heel portion of the last 25 so that when the tacks 28 are driven in they are permanently attached to the insole member 26, being clenched into a flattened condition by this metallic member.

80 After the tacks 27 have been removed, the edge of the upper 23 is trimmed to a desired extent, and at this stage of the process a shank stiffening element 29, in the form of a strip of steel, for example, may be applied to the insole member 26, as, for example, by means of a rivet or tack 30 at the rear end thereof.

85 Cement or similar adhesive is then placed on the inner surface of the sole 15, and especially upon the beveled marginal portion 19 thereof, and the sole is then firmly pressed down upon the last to cause it to unite in an adhesively bonded condition with the upper 23 and with the insole member 26. This may advantageously be accomplished in a cementing machine or the like.

90 Thereafter, the desired heel is affixed in the usual manner, as, for example, by trimming the outer marginal edge of the sole 15 around the heel portion or heel seat and by adhesively securing a wooden heel or the like, or by driving such 95 heel into position by means of tacks or similar instrumentalities.

95 Finally, the shoe embodies the appearance of Figure 6, in which, it will be noted, a Cuban heel 31 has been illustratively shown by way of example. In this finished shoe, the forward portion thereof presents the outwardly stylish and high-class appearance of a turned shoe, while the contour of the shoe at the shank portion is of a 100 highly efficient and smooth character.

105 In Figure 7, I have illustrated a modified sole 32 having the forward portion provided with the marginal shoulder 33 and with the channel 34, the shoulder merging, as hereinbefore mentioned, at or near the points 35 and 36 with a marginally beveled or tapered portion 37 which extends 110 around the shank and rear portions. In this construction, the heel portion of the sole member 32 is split longitudinally to provide a flap 38 which is ultimately disposed beneath the shoe, as shown 115 in Figure 8, for adhesive attachment to the heel breast 39 of a heel 40. This type of construction is particularly advantageous in connection with a French heel of the character shown in Figures 120 8 and 9; this heel having a gradually curved heel breast which merges in a graceful curve with the curvature of the shank portion of the sole.

125 In Figure 8, I have shown the flap 38 in its unfinished and unattached condition; and in Figure 9, this flap is shown in completed association with the heel 40.

130 The attachment of the upper 41 to the sole 32 is accomplished in practically the same manner as heretofore described, the forward portion thereof being stitched to the shoulder 33 in an inside-out condition, and then turned; while the shank and rear portions of the upper 41 are secured to the insole member and to the outer sole 32 by adhesive means.

135 In Figures 10 and 11, I have shown two typical insole members of the character that may be employed with my present construction. The member 26 of Figure 10 corresponds with the member 26 hereinbefore referred to, especially in connection with Figure 5. A strip of spring steel or similar rigid or reinforcing material 42 is shown secured to the under-side of this member at the points 43 and 44. The member 42, which is a shank stiffener, may be attached to the element 26 before the latter is placed upon 140

the last 25, or it may be associated therewith at any time thereafter, as hereinbefore described. In the latter case, it is preferable to employ only one nail or tack, as at the point 30 in Figure 5, 5 this tack encountering the metal plate hereinbefore referred to and being thereby clenched into a permanent flattened condition.

In Figure 11, the insole member 45 has been 10 illustratively shown with a shank stiffener 46 having a wider forward portion 47 which may, for example, be secured to the member 45 at the points 48 and 49.

It will thus be seen that I have provided a 15 shoe of new and unique characteristics and appearance, together with an improved and simplified process of producing such a shoe. Obviously, the specific details of procedure that I have outlined herein have been given merely by way of illustration and may be altered to suit 20 differing requirements. For example, the contour of the sole member may be altered in a variety of ways. The shoulder 16 may be of any desired extent and may extend either less than 25 the distance illustratively given or further toward the rear of the shoe; and the channel may be made to extend a proportionate distance. Similarly, the unstitched portion of the shoe 30 may be assembled in any desired manner, although I have found the procedure herein described as one which is highly efficient and satisfactory.

In general, it will be obvious that changes in 35 the details herein described and illustrated for the purpose of explaining the nature of my invention may be made by those skilled in the art without departing from the spirit and scope of the invention as expressed in the appended claims. It is therefore intended that these details be interpreted as illustrative, and not in a 40 limiting sense.

Having thus described my invention and illustrated its use, what I claim as new and desire to 45 secure by Letters Patent is—

1. In a shoe, an upper, and a sole therefor, the 50 lower edge of the forward portion of the upper being stitched to the corresponding forward portion of the sole, the rear portion of the upper and sole being unstitched, and the lower edge of the rear portion of the upper being adhesively secured to the corresponding rear portion of the sole.

2. In a shoe, an upper, a sole therefor, and a 55

shank piece overlying the shank portion of said sole, the lower edge of the forward portion of the upper being stitched to the forward portion of the sole, the rear portion of the upper and sole being unstitched, and the lower edge of the shank portion of the upper being adhesively sand- 80 witched between said shank piece and the shank portion of the sole.

3. In a turned shoe, a sole having a marginal shoulder around only the forward portion thereof and a channel located inwardly of said shoulder and terminating at the shank portion of the sole, and an upper having the lower edge of the forward portion thereof stitched to said shoulder, the rear portion of the upper and sole being unstitched, the stitches extending through said shoulder into said channel, and the lower edge of the rear portion of the upper being adhesively secured to the rear portions of the sole. 85

4. In a turned shoe, a sole having a marginal shoulder around its forward portion and having an unshouldered, tapered edge rearwardly of said forward portion, and an upper having the lower edge of its forward portion stitched to said shoulder and clearing the inner face of said sole and having the lower edge of its rear portion adhesively secured to the inner face of said unshouldered, tapered edge of the sole. 90

5. The herein-described method of making a 100 turned shoe, which consists in stitching the forward edge of an upper to the forward, marginally shouldered portion of a sole, leaving the shank and heel portion of the upper and sole unstitched, turning the assembly inside out to conceal said stitching, applying the assembly to a last, stretching the lower edge of the unstitched shank and heel portion of the upper over the last, and adhesively securing the unstitched portion of the sole to said lower edge of the unstitched shank and heel portion of the upper. 105

6. The herein-described method of making a 110 turned shoe, which consists in stitching the forward edge of an upper to the forward, marginally-shouldered portion of a sole, turning the assembly inside out to conceal said stitching, securing an insole member to a last, applying the turned assembly to said last, drawing and securing the lower edge of the unstitched portion of the upper over the marginal portion of said insole member, and finally cementing the unstitched portion of the sole to said lower edge. 120
